UNITED STATES PATENT OFFICE.

FREDRICK C. HORNSTEIN, OF INDIANAPOLIS, INDIANA.

INSULATED TROLLEY-CROSSING.

1,105,662.

Specification of Letters Patent.

Patented Aug. 4, 1914.

Application filed March 6, 1911. Serial No. 612,555.

To all whom it may concern:

Be it known that I, FREDRICK C. HORNSTEIN, of Indianapolis, county of Marion, and State of Indiana, have invented a certain 5 useful Insulated Trolley-Crossing; and I do hereby declare that the following is a full, clear, and exact description thereof, reference being had to the accompanying drawings.

10 The object of this invention is to improve the construction of trolley wire crossings for electric railway lines.

An important feature is the arrangement 15 of the crossing members so that they can be very quickly put together or separated.

The nature of the invention will be understood from the accompanying drawings and the following description and claim.

In the drawings Figure 1 is a plan view of 20 the crossing. Fig. 2 is the bottom view thereof. Fig. 3 is a central longitudinal section through the device. Fig. 4 is a section on the line 4-4 of Fig. 3. Fig. 5 is a section on the line 5-5 of Fig. 3. Fig. 6 is a section 25 on the line 6-6 of Fig. 3. Fig. 7 is a section on the line 7-7 of Fig. 3. Fig. 8 is a bottom view of one member of the crossing shown on a larger scale. Fig. 9 is a longitudinal vertical section on the line 9-9 of Fig. 8. 30 Fig. 10 is a transverse section on the line 10-10 of Fig. 9. Fig. 11 is a section on the line 11-11 of Fig. 8.

In detail, 10 represents one trolley wire and 11 the other crossing trolley wire. The 35 wire 10 runs over a long bridge 12 made of insulating material made of wood or fiber. The wire 10 and said bridge 12 are secured together by the metal frame 13 at each end of the bridge, which, as shown in Fig. 5, is 40 secured to the bridge by a bolt 14 passing through two lateral ears 15. There is a shoulder 16 on the metal piece 13 which abuts against the end of the bridge 12, and a clamp 17 is secured to the metal piece 13 45 by screws 18 and overlaps the trolley wire 10. There is also an approach 19 which is secured to the extreme ends of the metal pieces 13 by bolts 20 and which approaches surround the trolley wire.

50 The bridge 12 is centrally cut away on its underside at 22, as shown in Fig. 3, and adjacent said recess 22, at each side, a metal clip 23 is secured with a projecting finger 24 spaced away from the bridge so as to receive 55 a metal disk 35 of the crossing frame 26 for the trolley wire 11. The disk is provided

with notches or recesses 27 at diametrically opposite points to enable the disk to be slipped over the fingers 24, and then the disk is turned somewhat and is held between the 60 fingers 24 and the bridge 12. The trolley wire 11 runs over the metal crossing frame 26 and it is provided with approaches 28 secured by screws 29 similar to the approaches 19.

There is insulation 30 between the metal 65 pieces 13 and 23, which are secured to the bridge 12 for the purpose of electrically separating them as the former is attached to the trolley wire 10, while the latter is electrically connected with the trolley wire 11, 70 after the parts are in place. In the particular construction shown in Fig. 3 the part 30 is a strip of wood held in place at each end by little metal bands 31 which are secured by a bolt 32 to the lateral extensions from the 75 metal piece 13, as shown in Fig. 5. When the bridge 12 and the insulating strip 30 are made of wood, it is desirable that a plate of fiber or other insulating material 33 be located between them so as to protect the 80 bottom surface of the wooden bridge 12 from the arcing sparks as the trolley wheel passes over the strips 30. As shown in Fig. 7, the outer ends of the metal pieces 13 are provided with a central depression for the trolley 85 wire 10 and the clamp 17 has a central extension 34 which enters said depression for clamping the wire therein. It is, therefore, apparent that the two members of this crossing may be very quickly separated and as 90 quickly united. All that is necessary is to turn the two members somewhat with relation to each other so that the lower member will be disengaged from the fingers 24 of the upper member, and the opposite operation 95 will unite them.

The disk 35 of the lower member has a recessed upper surface in which the wire 11 extends or lies. The ends of said crossing frame 26 are also provided with a longitudinal recess 126 for said wire, substantially as indicated in Figs. 8, 9 and 11; and said frame is reinforced by vertical extensions or ribs 226 on each side, whereby it will stand the great strain to which it is subject. 105

I claim as my invention:

A trolley wire crossing including a pair of crossing trolley wires, a bridge-piece made of insulating material longitudinally over which one of said crossing wires extends, 110 metal pieces secured at each end of said bridge, means for clamping the trolley wire

to said metal pieces, a pair of metal pieces secured to said bridge near the middle thereof with fingers projecting toward each other and spaced apart from the body of the bridge, insulating strips between the metal pieces at the end of the bridge and the metal pieces near the middle of the bridge, a metal crossing frame secured to the other trolley wire and provided near its center with a disk 10 adapted to fit in the space between said fin-

gers and the body of said bridge and having oppositely located notches whereby it may be readily put in place or removed.

In witness whereof, I have hereunto affixed my signature in the presence of the witnesses 15 herein named.

FREDRICK C. HORNSTEIN.
